ENGINE STARTER

Youston Sekella, Elmira Heights, N. Y., assignor
to Eclipse Machine Company, Elmira, N. Y., a
corporation of New York

Application December 15, 1932, Serial No. 647,447

7 Claims. (Cl. 74—7)

The present invention relates to engine starters and more particularly to a starting device of the type which when actuated by a starting motor automatically engages and drives a member such as a gear on the flywheel of the engine to be started, and is automatically disengaged when the engine starts.

The reduction in the size and weight of flywheels for automotive engines to a point where such elements can hardly be recognized as flywheels has rendered it desirable in the interest of quiet and efficient operation that the starting device therefor be particularly adapted to the high torque and extremely rapid accelerations encountered. In particular it is desirable to provide as small a drive pinion as possible in order to secure a suitable gear reduction, and to incorporate special means for preventing the pinion from hunting or pumping back and forth as the engine goes over the compression points during cranking, and from rebounding against the engine gear when it is thrown out of mesh after the engine starts.

It is an object of the present invention to provide a starter drive which is particularly adapted to installations of this character, and which is efficient and reliable in operation particularly in connection with engines having low rotational inertia.

It is another object of the invention to provide such a device which is small in diameter and permits the use of a comparatively small driving pinion whereby it is adapted for mounting in a confined space, and furnishes a high gear reduction from the motor in connection with comparatively small engine gears.

A further object is to provide such a device which includes structure for preventing the driving pinion from hunting or pumping during the cranking operation.

It is another object of the invention to provide such a device which is constructed to prevent rebounding of the pinion toward the engine gear when it is thrown out of mesh.

Further objects and advantages will be apparent from the following description taken in connection with the accompanying drawing in which:

Fig. 1 is a side view partly in section of a preferred embodiment of the invention, showing the parts in their normal or idle position;

Fig. 2 is a similar view showing the parts in driving position;

Fig. 3 is a side view of the device embodying a balanced form of drive spring; and

Fig. 4 is a section taken substantially on the line 4—4 of Fig. 2.

Referring first to Fig. 1 of the drawing, there is illustrated a power shaft 1 which may be the extended armature shaft of a starting motor, not shown, and which carries and drives the starting mechanism. A hollow screw shaft 2 is freely journaled on the power shaft 1 and is provided at one end with a cylindrical enlargement or driven head 3 which is arranged to be driven from the power shaft 1 by means of a yielding driving connection in the form of a spring 4 suitably anchored as by means of a bolt 5 to the driven head 3, and by means of a bolt 6 to a driving head 7 fixed in any suitable manner to the power shaft 1. The driving and driven heads 7 and 3 are preferably arranged to telescope as indicated at 8 in order to form an internal support for the spring 4.

A nut member 9 is mounted on the screw shaft 2 in position to engage the threads 11 thereof, and is rigidly connected as by means of a barrel member 12 to a driving member in the form of a pinion 13 which is freely journaled directly on the power shaft 1 beyond the end of the screw shaft 2. The motion of the nut 9 along the threads 11 of the screw shaft is transmitted by the barrel 12 to the pinion 13 to cause said pinion to engage and disengage a member of the engine to be started such as a gear member 14. The driving position of the pinion 13 is determined by suitable stop means in the form of an abutment 15 threaded on the end of the screw shaft 2 in position to engage the nut 9 and limit its travel toward the engine member. The disengaging movement of the nut 9 is limited by the termination of the threads 11 on the screw shaft which are cut away adjacent the idle position of the nut 9 to leave a smooth portion 16 on the screw shaft on which the nut 9 may rotate forward freely.

The abutment 15 is provided with a radial flange 17, and a short spring 18 is provided within the barrel 12 adapted to bear against the end of said barrel and the flange 17 when the nut 9 is in idle position, and to thereby urge the nut into initial engagement with the ends of the screw threads 11 so as to insure the engagement of the nut with said screw threads when the screw shaft rotates forwardly. A light anti-drift spring 19 is provided in the barrel 12 between the flange 17 of the abutment 15 and the nut 9 for preventing the pinion from drifting toward the engine gear when the power shaft is stationary, due to vibration or other causes.

According to the present invention means are provided for yieldingly holding the pinion 13 in engagement with the engine gear 14 during the cranking operation so as to require a positive 5 thrust of considerable force to initiate the disengaging movement of the pinion. As here shown, this means comprises a plurality of radially movable detents 21 mounted in said barrel so as to project inwardly and engage a bevelled surface 22 on the edge of flange 17. The normal 10 position of the detents 21 is suitably determined as by means of shoulders 23 thereon, and means are provided for yieldingly urging the detents toward normal position in the form of an elastic 15 band 24 arranged to encircle the barrel 12 and bear on the outer sides of the shoulders 23 of detents 21. The detents 21 are preferably arranged to be unequally spaced about the barrel 12 as best shown in Fig. 4 in order to take 20 advantage of the multi-lead thread 11 to distribute the wear on the flange 17 of the abutment 15. That is to say, since the pinion runs off the ends of the threads 11, its angular relation with respect to the screw shaft when in 25 driving position will depend on which thread on the shaft happens to engage any particular thread space in the nut, and hence will vary according to the law of averages. Since the detents 21 are unequally spaced around the barrel 30 12 no two detents will engage the same portion of the flange 17 whereby the useful life thereof is prolonged. In the example here shown the thread 11 is a triple lead thread and there are three detents 21 spaced circumferentially at angles of 115°, 120°, and 125° around the barrel 12. 35

In Fig. 3 there is illustrated a modification of the yielding driving connection in the form of a spring 4a arranged with its terminal anchorages circumferentially spaced 180° apart. It will be 40 appreciated that this provides a balanced structure whereby wear on the bearings and noise due to looseness of the bearings is reduced.

In the operation of this device, starting with the parts in the position shown in Fig. 1, rotation of the power shaft 1 in the direction of the arrow (a) is transmitted through the spring 4 to the screw shaft 2 whereby the nut 9, by reason of its rotational inertia is caused to traverse along the threads 11 into engagement with the abutment 15, thereby forcing the detents 21 over the flange 17 and moving the pinion 13 to driving position as shown in Fig. 2. It will be noted that the pinion 13 is partly meshed with the engine gear 14 prior to the engagement of the detents 21 with the flange 17, so that rotation of the pinion 13 and barrel 12 is prevented by the inertia of the engine, and the detents 21 are accordingly forced over the flange 17 into the position illustrated in Fig. 2. Further rotation of 50 the power shaft 1 is transmitted through the nut 9 and barrel 12 to rotate the pinion 13 and cause the engine to be cranked.

During this cranking operation, minor accelerations of the engine gear 14 such as those 55 caused by the engine passing over its compression points are ineffective to move the pinion 13 away from its driving position by reason of the substantial resistance offered by the engagement of detents 21 with the flange 17. When the engine starts, however, the rapid acceleration thereof causes the pinion 13 to overrun the power shaft 1 and force the detents 21 back over the flange 17, whereby the pinion is thrown back 60 out of mesh with the engine gear. It will be understood that the rapid acceleration of the

pinion and barrel at this time causes a substantial centrifugal force to act upon the detents 21 which reduces materially the resistance of the detents 21 to the demeshing action. When the pinion 13 is thus thrown back out of mesh with the engine gear 14, the nut 9 runs off the ends of the threads 11, and the further longitudinal motion of the barrel and pinion assembly is arrested by the spring 18 so that the nut 9 when it comes to rest with respect to the screw shaft 2 is urged into initial engagement with the threads 11 as above described. 10

What is claimed is:

1. In an engine starter drive, a screw shaft, a nut threaded thereon, a member adapted to engage and drive a member of an engine to be started, an abutment on said screw shaft limiting the travel of the nut thereon in one direction, a barrel member connecting said nut and driving member, and cooperating means on said abutment and barrel member including a yielding detent for resisting the disengaging movement of the driving member. 15

2. In an engine starter drive, a screw shaft, a nut threaded thereon, a member adapted to engage and drive a member of an engine to be started, an abutment on said screw shaft limiting the travel of the nut thereon in one direction, a barrel member connecting said nut and driving member, and cooperating means on said abutment and barrel member including a flange on said abutment and a yielding detent in said barrel arranged to contact said flange and resist disengaging movement of the driving member. 20

3. In an engine starter drive, a screw shaft, a nut threaded thereon, a member adapted to engage and drive a member of an engine to be started, an abutment on said screw shaft limiting the travel of the nut thereon in one direction, a barrel member connecting said nut and driving member, said nut being arranged to run off the threads of the screw shaft when the driving member moves to idle position, and means for holding the driving member in engaging position including a plurality of yielding detents mounted on said barrel, and an element having a flange rigidly mounted on said screw shaft in position to cooperate with said detents. 30

4. In a starter drive a shaft, an actuating member mounted thereon for longitudinal movement with respect thereto and having an overrunning driving connection therewith, a member adapted to engage and drive a member of an engine to be started and rigidly connected to said actuating member, and means for holding the driving member in driving position including a detent mounted to move with said actuating member, and a member rigid with said shaft for engaging said detent. 45

5. In a starter drive, a screw shaft, a nut threaded thereon, a member adapted to engage and drive a member of an engine to be started and rigidly connected to said nut, and means for holding the driving member in driving position including a plurality of detents mounted to move with said nut, and a member rigid with said shaft for engaging said detents, said screw shaft having a multi-lead thread terminating adjacent the idle position of the nut whereby the nut runs off said thread when it is moved to idle position, said detents being unequally spaced circumferentially of the shaft. 60

6. In an engine starter drive, a power shaft, a driving head fixed thereon, a screw shaft journaled thereon and having a driven head, a coiled 75

drive spring surrounding said heads and anchored thereto, a nut threaded on said screw shaft, a driving member journalled on the power shaft, means rigidly connecting the pinion and nut, means on the screw shaft for limiting the longitudinal movement of the nut thereon to define the driving position of the pinion, the nut being arranged to run off the threads of the screw shaft when the pinion is returned to idle position.

7. In an engine starter drive, a power shaft, a screw shaft journalled thereon and connected to be driven thereby, a nut threaded on said screw

shaft, a driving member freely journalled on said power shaft, a barrel member rigidly connecting said nut and driving member, an abutment member on said screw shaft having an inclined flange within said barrel, a plurality of radially movable detents in said barrel in position to be forced over said flange when the driving member is moved to driving position, and yielding means for urging said detents against said flange to retain the driving member in driving position.
